[57] CLAIM

The ornamental design for a golf ball retriever, substantially as shown and described.

DESCRIPTION

FIG. 1 is a perspective view of my golf ball retriever showing my new design;

FIG. 2 is an enlarged perspective view thereof;

FIG. 3 is a front elevation thereof;

FIG. 4 is a side elevation thereof;

FIG. 5 is a rear elevation;

FIG. 6 is a bottom view thereof; and

FIG. 7 is a cross sectional view taken along lines 7—7 in FIG. 6.

The broken line showing of a handle in FIGS. 1 and 4 is for illustrative purposes only.
